UNITED STATES PATENT OFFICE.

THOMAS J. FLAGG, OF NEW YORK, N. Y., ASSIGNOR TO FISK, CLARK & FLAGG, OF SAME PLACE.

DESIGN FOR A SCARF-SHIELD.

SPECIFICATION forming part of Design No. 13,267, dated August 22, 1882.

Application filed September 19, 1881. Term of patent 14 years.

To all whom it may concern:

Be it known that I, THOMAS J. FLAGG, a resident of the city, county, and State of New York, have invented and produced a certain new and original Design for Scarf-Shields; and I do hereby declare that the following is a full, clear, and exact description thereof, reference being had to the accompanying drawing, and to the letters of reference marked thereon, making a part of this specification.

The annexed drawing shows a front view of my newly-designed scarf-shield.

This design relates to the configuration of scarf-shields, more especially of that class constructed with rounded upper outer corners for claudent scarfs.

In the drawing, A indicates a shield for a claudent scarf, constructed with an upper inwardly-curved edge, a, rounded corners bb , and 20 an inwardly-curved lower edge, c. Upon the

face of the shield, or of the lining with which it is covered, I stamp, paint, or impress two circles or circular lines, D D, one at each end, the center of the circle being by preference placed at points about midway between the center and ends of the shield, and between the upper and lower edges thereof.

I claim—

As a design for a scarf-shield, a shield, A, having rounded corners bb , with an intermediate inwardly-curved lower edge, c, substantially as shown and described.

In testimony whereof I have signed my name to this specification in the presence of two subscribing witnesses.

THOS. J. FLAGG.
